UNITED STATES PATENT OFFICE.

CHARLES G. PFEIFFER, OF PHILADELPHIA, PENNSYLVANIA, ASSIGNOR TO SPECIALTY ENGINEERING COMPANY, OF PHILADELPHIA, PENNSYLVANIA, A CORPORATION OF PENNSYLVANIA.

CHAIN CONVEYER.

Application filed May 22, 1922. Serial No. 562,603.

To all whom it may concern:

Be it known that I, CHARLES G. PFEIFFER, a citizen of the United States, residing at Philadelphia, county of Philadelphia, and 5 State of Pennsylvania, have invented certain new and useful Improvements in Chain Conveyers, of which the following is a specification, reference being had to the accompanying drawings.

10 This invention relates to chain conveyers of the type characterized by the provision of an endless belt of leather or fabric and a pair of endless chains, one secured to each edge of the belt to ensure positive and uniform movement of the belt under the influence of the driving mechanism.

An object of the invention is to provide a novel form of chain for a conveyer of this type in which each link is formed with 20 a flange so that the flanges along both sides of the loaded stretch of the conveyer may cooperate to form a trough-like structure, the flanges constituting side walls to prevent dislodgment of material from the belt.

25 In addition to the foregoing this invention comprehends improvements in the details of construction and arrangement of the correlated parts to be hereinafter set forth and particularly pointed out in the appended claims.

30 In the accompanying drawings, Fig. I is a view in top plan of several links forming part of a chain conveyer and illustrating the embodiment therein of my invention.

35 Fig. II is a view in side elevation of the links shown in the preceding figure.

40 Fig. III is a view in transverse section of a conveyer structure comprising a pair of chains and an intermediate belt supported therebetween.

Fig. IV is a view in top plan of several links showing an alternative construction.

45 Fig. V is a view in side elevation of the links shown in the immediate preceding figure; and

Fig. VI is a view in transverse section of a conveyer embodying the modified links.

With reference to Figs. I, II, and III of the drawings, 10 indicates as an entirety 50 my improved link, the specific structure of which includes a pair of side bars 11 and 12 connected at one end by means of an integral sleeve 13. The side bars converge

toward the sleeve thus reducing the length of the latter with respect to the distance 55 between the opposite or free ends of the side bars so that the side bars may overlap or enclose the ends of the sleeve of an adjoining link to form the chain, the connection being established through the medium 60 of a pin 14 suitably retained against dislodgment, and which passes through the sleeve and penetrates the appropriately apertured ends of the side bars. A lug 15 is formed on the side face of the bar 11 65 of each link and a flange 16 is formed on the top face of each bar 12 so that the flange is located in a plane at right angles to the face of the conveyer and parallel to the direction of movement. The flange follows 70 the curvature of the bar 12 so that in a series of links the ends of each flange are lapped by the ends of adjoining flanges to form a wall indicated generally at 17 in Figs. II and III, the latter showing the 75 assembly of a pair of chains and a belt conveyer. In the use of this form of link the connection between the edges of the belt, designated 18 is performed through the medium of longitudinal strips or blocks 19 80 secured to the under side of the belt along each edge and designed to be engaged by the lugs 15 of the links thus disposing the latter beneath the belt and almost wholly within the side edges thereof. The securing means such 85 as a rivet may penetrate both the lug and member 19 in order to fasten the same to the belt. This arrangement permits of the use of a comparatively wide belt in instances where the distance between the chains must 90 remain fixed by reason of the immovable mounting of the sprocket wheels over which the chains pass. The flanges 15, it will be noted rise perpendicularly above the surface 95 of the belt forming the walls 17 which enclose the edges of the belt and define a trough-like structure as shown in Fig. III. The presence of the flanges does not interfere with the articulation of the links during travel thereof around the sprocket 100 wheels or along the stretches. The material carried by the belt 18 is effectively retained thereon by reason of the enclosing side walls 17.

In instances necessitating the use of a narrower belt, the chain spacing remaining

fixed, recourse is had to the form of link shown in Figs. IV, V and VI and the method of assembly. The link, indicated generally at 20 is identical in construction 5 to the link 10 with the single exception that the flanges 16 are reversed with respect to their former position, and are formed with the side bars 11 instead of with the side bars 12. This change locates the flanges upon 10 the inner or adjacent sides of the chains so as to enclose the edges of a belt 21 which is narrower than the first mentioned belt 18 by an amount equal approximately to twice the 15 distance between the side bars 11 and 12 of a link. The assembly is shown in Fig. VI from which it will be noted that the belt, in this instance may be secured directly to the face of each lug 15. The links are located entirely beyond the edges of the belt 20 as distinguished over the first arrangement described. It will be apparent that the troughing flanges may be embodied in any other form of link than that described above and hence I do not limit myself to the exact 25 construction of the link but reserve the right to construct the combination of the troughing flange with any type of link adapted to cooperate with the flange in performing the contemplated result.

30 Having thus described my invention, I claim:

1. A conveyer comprising a continuous flexible supporting element, and an articulated means traveling and cooperating there- 35 with to form continuous retaining walls preventing dislodgment of material from the supporting element.

2. A conveyer comprising a continuous flexible supporting element, and means comprising a series of rigid elements in articulated relation cooperating with each other 40 to form a continuous retaining wall adapted to prevent dislodgment of material from the supporting element.

45 3. A conveyer comprising a continuous flexible supporting element, an articulated guiding element movable therewith, and means forming part of the latter to define a continuous retaining wall preventing dis-

lodgment of material from the supporting 50 element.

4. A conveyer comprising a continuous flexible supporting element, an articulated guiding means movable therewith, and a series of elements forming part of the latter 55 cooperating mutually to form a retaining wall to prevent dislodgment of material from the supporting element.

5. A conveyer comprising a continuous flexible supporting element, a chain forming 60 a guide for the edge of the supporting element, and a series of flanges, one formed with each link cooperating to define a continuous retaining wall preventing dislodgment of material from the supporting element. 65

6. A conveyer comprising a belt, a pair of chains one for each edge of the belt, means on each link affording connection thereof with the belt, and a flange on each link, said 70 flanges cooperating to form retaining walls along the edges of the belt.

7. A chain link for conveyers comprising, side bars, a cross connecting member, a flange formed on one of said bars to provide 75 a retaining wall, and a lug formed on one of said bars for attachment to a conveyer.

8. A chain link for conveyers comprising, a pair of side bars in converging relation, a sleeve connecting their adjacent ends, a 80 lug formed with one of said bars for attachment to the edge of a conveyer, and an up-standing flange formed with one of said bars to provide a retaining wall.

9. A conveyer comprising a flexible belt, 85 a chain secured to each edge of the belt, comprising links, and a rectangular flange formed with each link of the chain, said flanges cooperating to form retaining walls the upper 90 edges of which are straight.

In testimony whereof, I have hereunto signed my name at Philadelphia, Pennsylvania, this 16th day of May, 1922.

CHARLES G. PFEIFFER.
